UNITED STATES PATENT OFFICE.

WILLARD I. TWOMBLY, OF NEW YORK, N. Y., ASSIGNOR, BY MESNE ASSIGNMENTS, TO TWOMBLY MOTORS COMPANY, OF NEW YORK, N. Y., A CORPORATION OF NEW YORK.

INTERNAL-COMBUSTION ENGINE.

1,179,053.

Specification of Letters Patent. Patented Apr. 11, 1916.

Application filed February 1, 1910. Serial No. 541,233.

To all whom it may concern:

Be it known that I, WILLARD I. TWOMBLY, a citizen of the United States, residing in New York, county of New York, and State 5 of New York, have invented new and useful Improvements in Internal-Combustion Engines, of which the following is a description.

My invention pertains to that class of engines, or motors, in which power is derived 10 from the heat due to combustion of an explosive mixture within the cylinder of the engine.

My invention pertains to that particular 15 class of these engines known as "the two cycle type", in which an explosion takes place upon each revolution of the crank and has for its particular object to provide a simple, efficient and durable engine of this 20 character in which the products of combustion will be quite thoroughly expelled from the cylinder and not mixed with a fresh charge.

My invention further comprehends means 25 whereby the necessary charge is forced into the cylinder without creating pressure in the crank case as is usual, thus avoiding a tendency to oil leakage at the journal which is usually carried by the said crank case.

30 My invention also comprehends numerous other improvements in a construction of this type of engine which will be more plainly brought out in the description hereinafter.

In the drawings Figure I illustrates a vertical section of one form of engine embodying my invention. Fig. II is a top plan of the valve plate and the valve and other parts carried thereby, showing the piston rod in section. Fig. III is a vertical section of a 40 portion of the engine shown in Fig. I illustrating the valve and its cooperating parts in the positions taken when the crank has advanced 90 degrees from the position shown in Fig. I and in the direction indicated by the arrow in said figure. Fig. IV is a partial section showing the position of the valve when the crank has advanced 270 degrees from the position shown in Fig. I.

Fig. V is a partial section showing the valve 50 in section as viewed from the right and illustrating my method of taking up wear in the valve and maintaining a gas tight joint through the valve for operation of the piston rod therein. Fig. VI is a partial side elevation of the valve as viewed from the

left. Fig. VII is a top plan of the piston showing the arrangement of the inlet device and a horizontal section of the cylinder.

Referring to the drawings, particularly Fig. I, 1 represents a base frame, or casting, adapted to support the engine and carry the portion 2 so shaped as to form a proper crank case which is provided with the journal 3 carrying the main shaft indicated by dotted lines at 4. The main shaft carries 60 the crank 5 provided with the crank-pin 6 engaging the piston rod brasses 7 carried by the piston rod 8 and locked in fixed position thereon as by nut 9. The other end of the piston rod 8 is bushed in the usual manner and engages the wrist-pin 10 carried by the piston 11 working in the cylinder 12, the combustion chamber of which is indicated at 13. The lower part of the piston is provided with the expanded portion, or secondary piston, 14 working in the cylinder 15 in such manner as will hereinafter more plainly appear. The piston 11 is provided with heat radiating webs 16 and inlet device 17 shown in plan in Fig. VII, the function 70 of which will hereinafter more plainly appear. The piston 11 is provided with the usual piston rings and with a series of oil grooves 46 which serve to retain the oil which is injected into the cylinder with a charge of explosive mixture which will hereinafter be explained. The piston 14 may also be provided with the usual rings 75 as illustrated. The rod 8 passes through the sleeve 18 which is screw-threaded into the plug 19 which is free to revolve within certain limits within the yoke 20 of the slide valve 21. This valve operating upon the plate 22 serves to close the opening 23 into the crank case at all times and by its travel 80 to and fro governs the opening and closing of the port 24 as will hereinafter be explained. The port 24 leads into the chamber 25 which may be connected to any suitable source of explosive mixture as by means 85 of pipe connection 26.

27 represents the exhaust port which is uncovered by the piston 11 at the end of its stroke, while 28 represents the inlet port through which the explosive mixture is injected into the cylinder at the proper time 90 as will be explained.

29 is a fuel conducting chamber cast in the side wall of the cylinder in such manner as to receive a portion of the heat therefrom 105 110

and communicates with the interior of the cylinder through the port 28 when the same is uncovered by the piston, and at its lower extremity is connected with the cylinder 15 as by means of the port 30.

31 is the outer wall of the water jacket surrounding the combustion chamber 13 through which a water circulation may be maintained as by pipes 32 and 33 as indicated. This outer wall of the jacket is preferably made of light spun copper which may be snugly fitted upon the cylinder casting and then have shrunk thereon, at the lower extremity, a steel ring 34 so as to form a water tight joint. The upper end of the cylinder casting is provided with a hollow boss 35 into which is screwed the bushing 36 passing through the head of the jacket wall 31 in such manner as to firmly clamp that portion 15 of the jacket wall between the bushing and the casting so as to make a water tight joint. This is preferably done by providing the boss 35 with an annular groove upon its surface and providing the bushing 36 with an annular tongue adapted to register with the said groove and then, by screwing the bushing into the boss, crimp the shell 31 between the tongue and groove as illustrated.

The boss 35 is provided with a threaded opening 37 communicating with the combustion chamber 13 while 38 represents the usual spark plug which may be screwed into the bushing 36 so as to be in operative communication, through the opening 37, with the combustion chamber 13 within the inlet device 17 as will hereinafter be explained.

39 represents one of the gibs used for holding the slide valve 21 in place. The arrangement of the side valve and gibs upon the plate 22 and the ports covered by the valve are very clearly illustrated in Fig. II. The operation of the valve 21 by the rod 8 is shown in Figs. IV and V to which further reference will be made in describing the operation of the engine. In Fig. V the gibs 39 are shown in section as is also the slide valve 21 and plug 19. The sleeve 18 is screwed tightly into the plug 19 so as to form a gas tight joint therein and held from backing 40 out as by screw 40 and the plug is ground into the yoke 20 so as to form a tight joint and held in this position as by the spring 41 (see also Fig. VI) which is adjustable as by the screw 42 and presses upon the yoke 20 in such manner as to tend to move the slide valve 21 laterally so as to take up any wear between the plug and the yoke and maintain a gas tight joint therethrough. The piston rod 8 is provided with oil grooves 43 and when the engine is in operation I fill the lower portion 2 of the crank case with oil and the splashing of the crank in the oil serves to throw the same against the piston rod 8 and the valve 21 in such manner as to keep the rod lubricated within the bushing

18 and the valve 21 well lubricated upon its seat. The grooves 43 carry a sufficient quantity of the oil through the sleeve 18 and into the cylinder 15 to cause the piston working therein to be well lubricated. Further, a portion of this oil is carried around with the charge into the cylinder 12 in such manner as to keep the piston 11 lubricated therein as will hereinafter more plainly appear.

The operation of my improved engine is substantially as follows starting with the various parts in the positions shown in Fig. I: If the shaft 4 be revolved in the direction indicated by the arrow, the valve 21 will be moved in a right-handed direction holding the port 24 closed (see Fig. III) and the pistons 11 and 14 will be brought down so as to create a partial vacuum in the chamber 13 and the pressure in the cylinder 15 will be somewhat raised. This will cause the air from said cylinder to flow through port 30 into the chamber 29, causing pressure therein. Provided there is no fuel in the chamber 29 from previous running, when the piston 11 has been sufficiently lowered to uncover the exhaust port 27, air will enter therethrough and fill the cylinder 12 and with a little further travel the inlet port 28 will be uncovered and then the air compressed in the cylinder 15 will rush through the chamber 29 and port 28 into the cylinder 12 and practically displace the atmospheric air therein which will issue from the exhaust port 27, it being understood that the areas of piston 11 and piston 14 are so proportioned that the amount of air displaced by the piston 14 in one stroke is substantially the exact amount of air required to fill the cylinder 12 and combustion chamber 13 when the piston 11 is at the end of its stroke and cause atmospheric pressure therein—that is, just enough air will be forced by the piston 14 into the cylinder 12 at the end of the stroke to displace whatever air or products of combustion are contained therein at atmospheric pressure. This downward stroke of the piston or revolution of the shaft 4 through 180 degrees from that position shown in Fig. I will leave the position of the valve 21 as shown in Fig. I and the port 24 will have remained closed throughout the above outlined half revolution of the shaft. The ports 23 and 24 have been held closed by the valve 21 and no pressure has been created in the crank case as is usual in this type of engine. Further revolution of the crank shaft will cause the valve 21 to uncover the port 24 until the revolution shall have proceeded for approximately 270 degrees when the valve 21 will be in the position shown in Fig. IV and the port 24 will be wide open. During this quarter revolution the pistons 11 and 14 will be raised, causing the ports 27 and 28 to have been

closed by the piston 11 and compression to take place in the cylinder 12. The raising of the piston as above outlined will cause a partial vacuum in the cylinder 15 and the explosive mixture for the next charge will be drawn in from the pipe 26 through chamber 25 and port 24 into the cylinder 15. Further revolution of the crank will cause the pistons to be raised and the above outlined operations continued until the position shown in Fig. I is reached, when the valve 21 shall have again closed the port 24 and further revolution will produce the same results as above outlined during the first quarter except that the air forced from the cylinder 15 into the chamber 29 will now be replaced by the explosive mixture or fuel. When the revolution has continued until the exhaust port 27 has become uncovered 20 and the inlet port 28 is open an explosive mixture of fuel will now be forced into the cylinder 12 through the channel or opening 44 of the inlet device 17 so as to strike the end cylindrical wall 45 and be directed to the top of the combustion chamber 13 where this charge will mushroom and descend in such manner as to expel the atmospheric air which was in the cylinder. Further revolution will cause the same effect 25 as previously described save that an explosive mixture instead of air will be compressed into the chamber 13 and if this be fired as by means of the spark plug 38 as the crank shall pass its center as shown in Fig. I, the explosion caused by the firing of this mixture will cause the piston to be forced downwardly in a well-known manner until the exhaust port 27 is open and the products of combustion discharged to atmospheric 30 pressure when the inlet port 28 will be opened and a fresh charge of explosive mixture admitted as above described and continued operation be carried on as above outlined.

45 It will be obvious that the construction of the inlet device 17 is such that a portion of the fresh charge entering through the cavity 44 will always be retained therein during the upward stroke of the piston and will not mix with any products of combustion which may be left in the explosive chamber and by making the spark plug 38 extend sufficiently near the bottom of the cavity 44 the same, at the time of firing, will always be in a fresh mixture in no way vitiated by any products of combustion left in the cylinder. This mixture is readily fired by a spark and in turn will fire any poor mixture which may be in the compression chamber.

50 I do not wish in any way to limit myself to the exact details of construction or mode of operation outlined above which is given merely as a description of one form of engine embodying my invention and it is ob-

vious that wide changes may be made without departing from the scope of my invention which is as set forth in the following claims.

I claim—

1. An internal combustion engine of the two cycle type, comprising in combination a cylinder having a combustion chamber and a fuel pumping and compression chamber; a crank case to which the cylinder is fixed; a crank shaft journaled in said case; a piston working in the cylinder; a rod to connect the piston to the crank shaft; and means to maintain a substantially gas-tight joint between the pumping cylinder and the crank case comprising a fixed member interposed between the cylinder and crank case, a member slidable on the fixed member having a central opening for the passage of the piston rod, a plug carried by said sliding member adjacent the opening, and a sleeve adjustably carried by said plug and through which the piston rod passes substantially as and for the purpose specified. 70

2. An internal combustion engine comprising in combination a cylinder, a piston to work in the cylinder; a crank case to which the cylinder is fixed; a crank shaft journaled in said case; a rod to connect the piston to the crank shaft, a fixed plate interposed between the cylinder and crank case having a port connected with the fuel supply and communicating with the cylinder and having an opening for the passage of the piston rod; gibs fixed to the plate; a valve consisting of a plate slidably mounted between the gibs and fixed plate to control the opening and closing of the port in said latter plate by the movement of the piston rod; and a gas-tight connection between the valve and the piston rod, substantially as and for the purpose specified. 90

3. An internal combustion engine, comprising in combination a cylinder having a combustion chamber and a fuel pumping and compression chamber, the latter having a port to connect it to the source of fuel supply; a crank case to which the cylinder is fixed; a crank shaft journaled in the case; a piston to work in the cylinder; a rod to connect the piston to the crank shaft; and means moving with the piston rod to control the fuel inlet port to the pumping chamber and maintain a substantially gas-tight joint between said chamber and the crank case comprising a slide valve provided with a tapered orifice transverse to the piston rod, a tapered plug fitted into said orifice, a gland member carried by said plug in gas-tight relation to the piston rod, and resilient means to hold said plug in place. 110

4. An internal combustion engine comprising a power cylinder, a piston operating therein, a fuel pumping cylinder in a crank case adapted to contain a lubricant 120

4
and means for carrying the lubricant from the crank case into the said fuel pumping cylinder comprising a reciprocating member provided with oil carrying grooves traveling from the crank case into said fuel pumping cylinder.

5. An internal combustion engine, comprising in combination a cylinder having a combustion chamber and a fuel pumping 19 and compression chamber; a crank case adapted to retain a lubricant to which the cylinder is fixed; a crank shaft journaled in the case; a piston to work in the cylinder; a rod to connect the piston to the crank

shaft; means to prevent a ready passage of 15 fuel from the fuel pumping chamber into the crank case; means to connect the fuel pumping chamber to the combustion chamber; and a plurality of circular grooves in the piston rod to carry oil from the crank 20 case into the fuel pumping chamber in such manner that the same may be carried with the fuel into the combustion chamber to lubricate the same.

WILLARD I. TWOMBLY.
